UNITED STATES PATENT OFFICE.

JOHN F. SAYLOR, OF DODGE CITY, KANSAS.

WRENCH.

Specification of Letters Patent. Patented Aug. 5, 1919.

1,312,456.

Application filed March 14, 1919. Serial No. 282,624.

To all whom it may concern:

Be it known that I, JOHN F. SAYLOR, a citizen of the United States, residing at Dodge City, in the county of Ford and State of Kansas, have invented certain new and useful Improvements in Wrenches; and I do declare the following to be a full, clear, and exact description of the invention, such as will enable other skilled in the art to which it appertains to make and use the same, reference being had to the accompanying drawings, and to the letters and figures of reference marked thereon, which form a part of this specification.

This invention relates to an automobile wrench and is particularly adapted for loosening and tightening the nuts on a connecting rod of a motor vehicle engine, the specific use contemplated being the engagement of the nut on the rear connecting rod which is generally inaccessible by the ordinary wrench.

In the drawings,

Figure I designates a partially sectional view of an explosion engine to which my invention is adapted, and

Fig. II is a detail perspective view of the wrench.

Referring now to the drawings by numbers of reference:

1 designates an engine casing and 2 an opening therein, usually covered by a removable plate. In the casing is a crank 3 which drives a piston 4 in the cylinder 5 by the usual connecting rod 6 fastened to the crank by the coupling 7 through the nut or nuts as indicated at 8 on the connecting rod

9. In order to have access to the nut, I have provided a wrench as best shown in Fig. II, as comprising a rigid jaw 10, a handle 11, 40 a shank connecting the handle and rigid jaw, said shank being bent to form a double elbow portion 12 with a portion 13 inclined from the double elbow portion and terminally supporting the jaw, the jaw and handle being in axial alinement so that when the oppositely projecting portions 14 and 15 of the handle are grasped to turn the wrench, the nuts may have power alined thereto in axial alinement at the point of 50 application of the power. The double elbow portion 12 is in no wise a hand grip or handle but is an off-set whereby the wrench may be introduced through the slot 2 in a manner to permit the body 10 to engage the 55 nut.

Having thus described my invention, what I claim as new therein, and desire to secure by Letters-Patent, is:

As a new article of manufacture, a wrench 60 for connecting rods of motor vehicle motors comprising a rigid jaw, a handle, and a shank connecting the handle and the jaw, said shank being bent to form a double elbow portion connected to the handle and a 65 portion inclined from the double elbow portion and terminally supporting the jaw, the jaw and handle being in axial alinement, the jaw being rigid with the handle whereby the shank may be turned through the medium 70 of the handle.

In testimony whereof I affix my signature.

JOHN F. SAYLOR.
